PATENTED MAR. 17, 1903.

G. A. SCHOELLER.

SIGHTING ATTACHMENT FOR GUNS.

APPLICATION FILED AUG. 7, 1902.

NO MODEL.

UNITED STATES PATENT OFFICE.

GUSTAV A. SCHOELLER, OF MÜLHEIM-ON-THE-RUHR, GERMANY, ASSIGNOR
TO FRIED. KRUPP, OF ESSEN-ON-THE-RUHR, GERMANY.

SIGHTING ATTACHMENT FOR GUNS.

SPECIFICATION forming part of Letters Patent No. 722,761, dated March 17, 1903.

Application filed August 7, 1902. Serial No. 118,767. (No model.)

To all whom it may concern:

Be it known that I, GUSTAV A. SCHOELLER, a subject of the Emperor of Germany, and a resident of 2 Gustavstrasse, Mülheim-on-the-5 Ruhr, Germany, have invented certain new and useful Improvements in Sighting Attachments for Guns, of which the following is a specification.

This invention relates to gun attachments, 10 and especially to attachments for ships' guns and sea-coast guns. In such attachments several slides or slide-pieces (at least two) are employed for making the several corrections in the traverse. For example, in a two-15 slide attachment one slide (the sighting-slide) carries the rear sight, while the other slide carries a scale for corrections in traversing, resulting from movement of the target, while on the head of the attachment is a fixed scale 20 provided for corrections in training, to be made with respect to lateral aberrations of the shot. The indexes belonging to the respective scales are mounted upon the sight-slide and on the second slide-piece. In attach-25 ments heretofore known the first slide-piece (the sight-slide) is movable on the second, and the latter is movable on the head of the attachment, and the adjustment of the sight-slide alone, as also the adjustment of 30 this sight-slide together with the second slide-piece, is effected by means of a special adjusting-screw for each.

The object of this invention is to enable both the adjustment of the sight-slide alone, 35 as well as the adjustment of said sight-slide and second slide together, to be accomplished by one and the same adjusting-screw. This object is accomplished, according to the present invention, by having both slide-pieces 40 slidable upon the attachment-head independ- 45 ently of each other and providing couplings through which the second slide-piece may be connected either with the first slide-piece or with the head of the attachment.

An illustration of this invention is shown 50 in the accompanying drawings, in which—

Figure 1 is an elevation. Fig. 2 is a section on the line 2 2, Fig. 1, looking from the left; and Fig. 3 is a detail view.

The attachment-rod A is provided with a 55 head a, designed for the reception of a sight-

ing-slide B. The sight-slide B carries a notch or spider-lines or the like of known construction and is provided on its under sliding face with a nut b of dovetailed section, which trav- 55 els in a correspondingly-formed longitudinal groove C of the head of the attachment-rod. Engaging with the thread of this nut b is a screw-spindle D, which is rotatable, but not longitudinally movable, in the attachment- 60 head. One end of the spindle D is provided with a turning head F. On the head a of the attachment-rod is secured a track G, formed with a longitudinal slot J. Between the track G and the plate-like extension b' of the sight- 65 slide B, lying parallel to the side face of the attachment-head, is arranged a slide-piece K, which has a section formed by two straight portions connected by an offset and is guided upon the outer under face of the extension b' 70 and the upper inner face of the track G. Rigidly connected with the slide-piece K is a screw-bolt L, which extends through slot J of the track G. Upon this screw-bolt L is fitted a nut M, constructed in the form of a toothed 75 wheel, upon which is fixed a grip-wheel S through the medium of a screw s. The screw-bolt L is provided with a right-handed thread, so that by turning the grip-wheel S in the direction of the hands of a clock the slide- 80 piece K and the track G are pressed together through the medium of the nut M, and can thus be coupled by friction. The teeth m of the nut M are in mesh with a gear-wheel N, in the nave n of which a screw-bolt O is se- 85 cured against rotation and axial movement through the medium of an angular portion P on said screw and a nut Q. The screw-bolt O is provided with a left-handed thread, ex- 90 tends through the longitudinal slot R of the extension b', and extends in driving connec- 95 tion with the internal thread of the slide-piece K. On the free end of the screw-bolt O a head o is provided, which by a turning of the screw-bolt O in the direction of the hands of a clock impinges the inner face of the extension b'. By a further rotation the screw-bolt O presses the slide-piece K upon the extension b' of the sight-slide, so that the slide-piece K is coupled with the sight-slide 100 by friction. The opposed position of the screw-bolts O and L is so determined that

when the coupling between the sight-slide B and the slide-piece K is released said coupling is effected between the track G and said slide-piece K, and vice versa.

5 The track G carries a scale g, whose pointer g' is arranged upon the slide-piece K. Above these marks and also upon the slide-piece K is a second scale k, whose pointer k' is located upon the sight-slide. The scale g, with the 10 pointer g', serves in the illustration under discussion for establishing corrections in the horizontal training necessitated by lateral aberrations of the shot, while upon the scale k, with the pointer k', are established corrections in horizontal training due to wind or 15 specific velocity or the velocity of the target.

The toothed gear m N is covered by a protecting-cap T, Figs. 2 and 3, which is mounted on the scale-slide K. Upon the face of 20 the wheel S is an arrow U, while upon the protecting-cap T are arranged two marks—to wit, S (lateral aberration) and M, (range.) The arrow points to mark S (shown in dotted lines) when the slide-piece K is coupled with 25 the sight-slide B—that is to say, the scale k is fixed relatively to its pointer k'—while the point of this arrow U indicates the mark M (shown in full lines) when the slide-piece K is coupled with the track G—that is to say, 30 the scale g is in fixed relation to its pointer g'.

The manipulation and mode of operation of the described arrangement are as follows: It is assumed that the several parts of the attachment are in the position shown in the 35 drawings. The two pointers g' and k' stand at the zero-points in relation to their respective scales, Fig. 1, and the arrow U points to the mark M, Fig. 3—that is to say, the slide-piece K is coupled with the track G by the 40 parts L M, while the coupling K O o is released, Fig. 2. It is now desired to establish corrections in the horizontal training due to the lateral aberration of the shot. This adjustment is accomplished by shifting the 45 pointer g' along the scale g, and is only possible when slide-piece K is coupled with the sight-slide b and uncoupled from the track G. This is attained by turning the grip-wheel S in a direction opposite to the movement of the hands of a clock until the arrow 50 indicates the mark S. By this movement the nut M of the spindle L is released. Simultaneously the screw O will be turned, through the medium of the teeth m and the toothed 55 wheel N, in the direction of the hands of a clock, so that the coupling between the slide-piece K and the sight-slide B is established. If now the adjusting-screw D is turned through the medium of the grip-wheel F, it follows 60 that the sight-slide B, together with the slide-piece K, will move along the track G, so that the corrections of the horizontal training required by lateral aberrations of the shot are established through the medium of the pointer g', carried by the slide-piece K, in connection 65 with scale g. We must now establish corrections in the horizontal training necessitated

by wind or specific velocity or by the velocity of the target through the medium of the scale k and its pointer k' without altering the adjustment that has already been established.

For this purpose the scale g must be coupled immovably with relation to its pointer g', while the coupling of the scale k to its pointer k' must be released. This is accomplished by 70 shifting the arrow U, Fig. 3, upon the mark M. By this means the nut M turns in the direction of the hands of a clock, the screw O turning in the opposite direction, so that the slide-piece K is coupled with the track G, 80 while the coupling of the slide-piece with the sight-slide B is released. By throwing the adjusting-screw D now it is obvious that the sight-slide B moves relatively to the slide-piece K, which remains at rest with the track 85 G, so that the corrections in the horizontal training necessitated by the wind, &c., may be indicated by the pointer k' on the scale k.

It is obvious without further discussion that each of the two adjustments can be made 90 independently of the other by the coupling or uncoupling of the appropriate parts—that is to say, by oscillating the arrow U between the marks L and M—and that the details may be varied without departing from the spirit of 95 the invention.

Having thus described the invention, the following is what I claim as new therein:

1. A sighting attachment for guns, having two independently-slidable slide-pieces, a common adjusting-screw for said slide-pieces, and couplings fixing one of said slide-pieces to the other or to the attachment-head at will, whereby adjustment of one slide-piece alone or both slide-pieces together may be made by 100 one and the same adjusting-screw.

2. A sighting attachment for guns, having two independently-slidable slide-pieces, a common adjusting-screw for said slide-pieces, and couplings, consisting of screw-bolts and 110 nuts, fixing one of said slide-pieces to the other or to the attachment-head at will, whereby by adjustment of one slide-piece alone or both slide-pieces together may be made by one and the same adjusting-screw.

3. A sighting attachment for guns, having an attachment-head, independently-slidable slide-pieces, a single adjusting-screw therefor, and oppositely-working couplings for the respective slides connecting one slide to the 120 other, or to the attachment-head, and a connection between the couplings causing one to connect as the other disconnects, and vice versa.

4. A sighting attachment for guns, having 125 an attachment-head, independently-slidable slide-pieces, a single adjusting-screw therefor, and oppositely-working couplings for the respective slides consisting of right and left handed screw-bolts and nuts therefor, connecting one slide to the other or to the attachment-head, and a connection between the couplings causing one to connect as the other disconnects, and vice versa.

5. A sighting attachment for guns, having an attachment-head, independently-slidable slide-pieces, a single adjusting-screw therefor, and oppositely-working couplings for the respective slides consisting of right and left handed screw-bolts and nuts therefor, connecting one slide to the other, or to the attachment-head, and a connection between the couplings consisting of toothed wheels 35
10 secured to each coupling, causing one to connect as the other disconnects, and vice versa.

6. A sighting attachment comprising the attachment-head the sight-slide thereon, the screw adjusting the sight-slide, a slide-piece, 40
15 a screw-bolt for connecting the sight-slide and slide-piece, threaded in one of said parts and working in a slot in the other, and provided with turning means, a slide-track fixed on the attachment-head, a screw-bolt for connecting the slide-piece with the slide-track, 45
20 fixed in one of said parts and working in a slot in the other, and having a nut for clamping said parts together.

7. A sighting attachment comprising the attachment-head, the sight-slide thereon, the screw adjusting the sight-slide, a slide-piece, 45
25 a screw-bolt for connecting the sight-slide and slide-piece, threaded in one of said parts and working in a slot in the other, a slide-track 50
30 fixed on the attachment-head, a screw-bolt

for connecting the slide-piece with the slide-track, fixed in one of said parts and working in a slot in the other, and having a nut for clamping said parts together; said screw-bolts being oppositely threaded, and intermeshing gear-wheels, one connected with one of the screw-bolts, and the other connected with the nut. 35

8. A sighting attachment comprising the attachment-head, the sight-slide thereon, the screw adjusting the sight-slide, a slide-piece, 40
45 a screw-bolt for connecting the sight-slide and slide-piece, threaded in one of said parts and working in a slot in the other, a slide-track fixed on the attachment-head, a screw-bolt for connecting the slide-piece with the slide-track, fixed in one of said parts and working in a slot in the other, and having a nut for clamping said parts together; said screw-bolts being oppositely threaded, and intermeshing gear-wheels, one connected with one of the screw-bolts and one connected with the nut and provided with a grip-wheel. 50

The foregoing specification signed at Dusseldorf, Germany, this 24th day of July, 1902. 55

GUSTAV A. SCHOELLER.
